UNITED STATES PATENT OFFICE

156,232

DESIGN FOR A HOUSEBOAT

Clyde E. Gray, Port Arthur, Tex.

Application October 20, 1948, Serial No. 149,193

Term of patent 14 years

(CL. D71—1)

To all whom it may concern:

Be it known that I, Clyde E. Gray, a citizen of the United States, residing at Port Arthur, in the county of Jefferson and State of Texas, have invented a new, original, and ornamental Design for a Houseboat, of which the following is a specification, reference being had to the accompanying drawings, forming a part thereof.

In the drawings—

Fig. 1 is a perspective view looking downwardly and toward the rear end of the houseboat, and showing my new design.

Fig. 2 is a side elevational view looking from the right-hand side of Fig. 1.

Fig. 3 is a side elevational view looking toward the left-hand side of Fig. 1.

Fig. 4 is a plan view, and

Fig. 5 is an end view looking at the front end

of the houseboat and toward the opposite end of Fig. 1.

I claim:

The ornamental design for a houseboat, substantially as shown.

CLYDE E. GRAY.
